P. EBBESEN

LOCK

Filed Jan. 5, 1924

UNITED STATES PATENT OFFICE.

PETER EBBESSEN, OF HOLLYWOOD, CALIFORNIA.

LOCK.

Application filed January 5, 1924. Serial No. 684,617.

To all whom it may concern:

Be it known that I, PETER EBBESSEN, a citizen of the United States, and resident of Hollywood, in the county of Los Angeles and 5 State of California, have invented certain new and useful Improvements in Locks, of which the following is a specification:

This invention relates to locks especially adapted for use on automobiles, though not 10 necessarily restricted to such use.

An important object of this invention is to provide a lock which will automatically hold the door in closed position in such a manner that rattle is prevented.

15 A further object of the invention is to provide a lock of the character specified which is simple to operate, durable in use and cheap to manufacture.

Other objects and advantages will be apparent during the course of the following 20 description.

In the accompanying drawing, forming a part of this application, and in which like numerals are employed to designate like 25 parts throughout the same,

Figure 1 is a perspective of the improved lock applied to an open vehicle body.

Figure 2 is an enlarged perspective of the locking disk and associated elements.

30 Figure 3 is a perspective of a hand grip embodied in the invention,

Figure 4 is a perspective of the improved lock applied to the door of a closed motor vehicle.

35 In the drawing wherein for the purpose of illustration is shown a preferred embodiment of the invention the numeral 5 designates the body having side doors 6 adapted to be closed by the improved lock forming 40 the subject matter of this application.

As illustrated in Figure 2 one corner of the door is cut away or recessed to receive a locking disk 8 connected to the door by means of a pivot member 9. It will be seen 45 that the outer surface of the locking disk or wheel 8 is approximately flush with the adjacent vertical edge of the door and the wheel projects beyond the inner and outer surfaces of the door.

50 In carrying out the invention, the wheel 8 is provided with an eccentric slot 10 opening out through the periphery of the wheel and adapted to receive a locking arm 11

carried by the vehicle body and projecting a proper distance into the door-receiving opening. When the door is closed the wheel or disk 8 is rotated so that the locking arm 11 is received in the eccentric slot 10 whereby the door is drawn tightly to its closed position. Due to the eccentric arrangement of the slot 10, the disk 8 holds the door securely in closed position and prevents rattling.

One side of the disk 8 and more particularly the side opposite the slot 10 is recessed and is therefore substantially lighter than the side having the slot 10 so that the disk will turn of its own accord and move to its operative position.

Figure 1 illustrates that the outer side of the door is provided with a fixed knob 20 adapted to be engaged by the fingers of the operator while the periphery of the disk is provided with a knob 21, adapted to be engaged by the thumb of the operator. When it is desired to position the disk 8 for engaging the arm 11 it is merely necessary to grasp the knob 20 and the knob 21 and move the knob 21 downwardly in the direction of the fixed knob. The door is now slowly swung to a closed position and the disk will move to its operative position when the arm 11 is received in the eccentric slot.

The inventive idea involved in this application may also be carried out in connection with a closed vehicle body 25 having a full length door 26. In this case, the disk 8 may be operated from the inside or the outside and is provided on its inner side adjacent the slot 10 with a knob 28 adapted to be engaged by one's fingers or thumb and immediately above the disk the door 26 is provided with a fixed bracket 30 constituting a hand grip. When the knob 28 is moved upwardly in the direction of the fixed bracket 30 the disk 8 is rotated so that it is moved to its inoperative position and the door may be conveniently opened. When it is desired to open the full length door 26 from the outside, it is merely necessary to move the knob 21 downwardly in the direction of the knob or bracket 20 present in the full length door.

A lock constructed in accordance with this invention may be conveniently applied to a vehicle without marring the appear-

ance of the vehicle, and by reason of the travel of said knob to limit the turning of simple arrangement of the parts, jamming the disk. or sticking of the lock is unlikely, and the lock may be conveniently manipulated from 5 the outside or the inside of the vehicle.

Of course, in the actual manufacture of the lock, the same may be refined and slight changes in arrangement and construction of parts may be made without departing from 10 the spirit of the invention, and the scope of what is claimed.

Having thus described the invention, what is claimed is:—

- 15 1. The combination with a door having a recessed portion, of a rotatable locking disk partly received in said recessed portion and having a locking slot extending out through the periphery thereof, a locking bolt adapted to be received in said slot, and a knob 20 carried by the periphery of said disk, a portion of the door being in the path of

2. The combination of a door, a locking disk rotatably carried thereby and having an eccentric slot opening out through the periphery thereof, a locking arm arranged parallel to the axis of said disk and adapted to be received in said slot, the periphery of said disk being provided with a knob, and a fixed knob carried by the door and extending parallel to said first named knob.

3. A lock comprising a disk having means whereby the same may be rotatably connected to a door and being provided with an eccentric slot opening out through the periphery thereof, the side of said disk with the slot being weighted, knobs carried by opposite sides of said disk, and a fixed bracket arranged between said knobs.

PETER EBBESSEN.
